FIG.1

FIG.2

FIG.3

FIG.4

FIG.5

FIGURE 1 is a three-quarter front perspective view of a rollable appliance support showing my new design;

FIGURE 2 is a front view thereof in enlarged scale;

FIGURE 3 is a broken bottom view thereof;

FIGURE 4 is a broken side elevational view thereof; and

FIGURE 5 is a rear elevational view thereof.

The characteristic features of my design reside in the ornamental configuration of a rectangular, relatively narrow and elongated housing which overlies and spaces apart two compact groups of wheels, the wheels in each group being arranged in closely spaced transverse rows recessed within the associated extremity of the elongated housing.

I claim:

The ornamental design for a rollable appliance support, substantially as shown and described.
